DESIGN FOR A GAME BOARD

Isabel Meeker, New York, N. Y.

Application July 23, 1941, Serial No. 102,394

Term of patent 7 years

To all whom it may concern:

Be it known that I, Isabel Meeker, a citizen of the United States, residing at New York, in the county of New York and State of New York, have invented a new, original, and ornamental Design for a Game Board, of which the following is a specification, reference being had to the accompanying drawings, forming part thereof.

I claim:

The ornamental design for a game board, as shown.

ISABEL MEEKER.
